UNITED STATES PATENT OFFICE.

OSCAR J. D. MANEVAL, OF LYNDEN, WASHINGTON.

DEVICE FOR RAISING SUNKEN SHIPS.

1,198,738.

Specification of Letters Patent. Patented Sept. 19, 1916.

Application filed July 9, 1915. Serial No. 38,958.

To all whom it may concern:

Be it known that I, OSCAR J. D. MANEVAL, a citizen of the United States, residing at Lynden, in the county of Whatcom, State 5 of Washington, have invented certain new and useful Improvements in Devices for Raising Sunken Ships; and I do hereby declare the following to be a full, clear, and exact description of the invention, such as 10 will enable others skilled in the art to which it appertains to make and use the same.

This invention relates to improvements in devices for raising sunken ships.

One object of the invention is to provide 15 a novel and simple device by means of which a sunken ship can be readily located and a grapple engaged with the ship so that the same can be pulled to the surface.

Other objects and advantages will be apparent from the following description when 20 taken in connection with the accompanying drawing.

In the drawing: Figure 1 is an elevation of a portion of a sunken ship, with my invention applied thereto, Fig. 2 is a plan view of the drum, Fig. 3 is an elevation of the drum and attached parts, Fig. 4 is a transverse section on the line 4—4 of Fig. 2, Fig. 5 is a transverse section on the line 30 5—5 of Fig. 2, Fig. 6 is an enlarged elevation of the grapping hook engaged with the member carried by the sunken ship, Fig. 7 is a vertical section through the parts shown in Fig. 6, and Fig. 8 is a top plan view of the parts shown in Fig. 6.

Referring particularly to the accompanying drawing, 10 represents the deck of a sunken vessel and 11 the hold. In the deck is countersunk a plate 12 having a counter-sunk opening 13 formed therein. In the deck, below this opening is formed an opening 14. Extending vertically through this opening is a stem 15, the lower end of which is formed with a large counter-balancing 45 weight 16. Formed on this stem above the plate is an enlargement 17 above which is a reduced neck 18 surmounted by an enlarged head 19. Formed vertically through the enlargement, the stem and the weight are two 50 openings 20, through which are passed the two cables 21. Mounted on the lower side of the weight 16 are three guiding rollers 22 between which the lower ends of the cables pass.

55 In the hold of the ship is mounted a frame

23 which supports a shaft 24 carrying a winding drum 25. In this drum are mounted two grooved rollers 26, and engaged under these two rollers is the intermediate portion of the cable of which the cables 21 60 are the ends. Pivotedly mounted in the frame 23, adjacent the roller, is a spring-pressed guiding and tensioning device 25' for insuring the proper and even winding of the cable. 65

Pivotedly mounted in the frame 23 is a lever 44, the outer end of which is supported by the spring 45. Passing over one end of the drum, and secured at one end to the frame, and at the other end to the lever, is 70 a strap brake 46.

Connected to the outer ends of the cable 21 is a ring 27 carrying a chain 28 having a clevis 29 attached thereto. Connected to this clevis is a float 30 which carries a second cable 31 connected to the cables 21 and by means of which said cables may be easily and quickly reached for the application of the grapple which will now be described. 75

A grapple is used for engagement with 80 the head 19. This grapple includes a block 32 through which is formed a longitudinal bore 33. On the upper end of the block is a bail 34 carrying a ring 35 for the attachment of a cable (not shown) which is carried by the rescue ship and by means of which the sunken ship is raised. 85

Pivotedly mounted on the sides of the block are the levers 37, the lower ends of which are provided with the inwardly directed hooks 38 adapted to embrace the head 19 and to engage under the shoulder formed therebelow. The upper ends of the levers are provided with pulleys 39 through which is passed a cable 40 having a ring 41 for attachment of a cord 42. An upward pull on this cord will swing the levers on their pivots so as to spread the hooks apart, the hooks being returned to normal engaging 90 position by the springs 43. 100

In the operation of the device, when the ship is about to sink the float is released. When the ship sinks, the float will rise to the surface of the water, unwinding the cables from the drum as it rises. The float indicates, to the salvaging ship, the position of the sunken ship. The float is pulled up and the cables passed through the grapple, after which the grapple is permitted to slide down the cables until its hooks engage un- 105 110

der the head 19. It will, of course be understood that the grapple has a cable attached thereto so that the sunken ship can be pulled up.

5. What is claimed is:

In a device for indicating the position of a sunken ship, a drum mounted in the ship, a single length of cable, said drum having a longitudinal slot formed therein, a pair of
10 grooved rollers mounted in the slot for the

reception of the bight portion of the cable thereunder, and a float carried by the ends of the cable.

In testimony whereof, I affix my signature, in the presence of two witnesses.

OSCAR J. D. MANEVAL.

Witnesses:

FANNIE M. JENKINS,
PEARL TUCKER.
